[57] CLAIM

The ornamental design for a figurine of a camel, substantially as shown.

DESCRIPTION

FIG. 1 is a front end perspective view of a figurine showing our new design;

FIG. 2 is a side elevational view of FIG. 1, the other side being a mirror image thereof;

FIG. 3 is a rear end perspective view of FIG. 1; and FIG. 4 is a top plan view of FIG. 1.
